UNITED STATES PATENT OFFICE.

EDWARD SMULSKI, OF BROOKLINE, MASSACHUSETTS.

REINFORCED CONCRETE CONSTRUCTION.

1,223,529.

Specification of Letters Patent.

Patented Apr. 24, 1917.

Application filed April 12, 1915. Serial No. 20,599.

To all whom it may concern:

Be it known that I, EDWARD SMULSKI, a citizen of the United States, residing at Brookline, in the county of Norfolk and State of Massachusetts, have invented an Improvement in Reinforced Concrete Construction, of which the following description, in connection with the accompanying drawings, is a specification, like characters on the drawings representing like parts.

This invention relates to concrete reinforcing means and among other objects provides a strong, simple and effective construction.

The character of the invention may be best understood by reference to the following description of an illustrative embodiment thereof shown in the accompanying drawing, wherein:

Figure 1 is a plan of illustrative reinforcing means shown herein as embodying the invention;

Fig. 2 is a vertical transverse section taken on line 2—2 of Fig. 1;

Fig. 3 is a vertical transverse section taken on line 3—3 of Fig. 1; and

Fig. 4 is a detail to be referred to.

Referring to the drawings, 1 designates a slab of concrete adapted to be mounted on the heads 3 of columns 5, or on other appropriate supports.

The upper portions of the slab directly above the columns experience the greatest tension stress, while the lowest portions of the slab above the columns experience the greatest compression stress. In the central area or region of the slab between the columns the conditions are reversed, and the lower surface portion thereof experiences the greatest tension stress, while the upper surface portion thereof experiences the greatest compression stress.

It is a well-known fact that concrete is strong in compression but weak in tension. The object of the present invention is to provide suitable reinforcing means for the portions of the concrete under tension. To accomplish this, a reinforcing unit is provided above each column, and a reinforcing unit is provided in the central portion between the columns.

The reinforcing units above the columns each comprises a series of interrupted substantially circular bars 7 preferably concentrically arranged and of progressively increasing diameters. As well shown in Fig.

2, these bars are located in the upper portion of the slab above the column which is under the greatest tension stress.

Each of these bars has overlapping end portions 9 terminating in downwardly bent ends 11 which serve the dual function of anchoring the ends of the bar to prevent them spreading open, and also to position the bar the appropriate distance from a mold form to produce the greatest strengthening effect.

The overlapped portions form in effect a splice for connecting the ends of the bar. The splices of the series of bars preferably are not arranged in radial alignment, but are distributed circumferentially of the series as shown in Fig. 1, thereby providing a uniform arrangement.

Directly beneath the circular series of tension bars is arranged a series of radial bars 13 and 15. To anchor these bars they are provided with downwardly and outwardly bent portions forming hooks 17 and 19. The hooks 17 are anchored around an inner circular bar 21, and the hooks 19 are anchored around a circular bar 23, having a diameter slightly larger than that of the circular bar 21. As shown herein, the radial bars 13 are arranged alternately with the radial bars 15.

To contribute to the strengthening of the central region of the slab located between the columns some of the radial bars may be somewhat longer than others of the radial bars.

An assembly of circular and radial bars such as described will be provided in the slab above each column. While in Fig. 1 merely two columns and their reinforcing units are shown, it is to be understood that similar columns and units are provided at the other two corners of the slab.

Next will be described the reinforcing unit for the central region of the slab. To this end there is provided a series of bars 25, which are closely arranged in and near the lower surface of the central region of the slab which is under the greatest tension stress, and spread or flare divergently outward in opposite directions from the center of the slab into regions thereof which are under less tension stress. A similar series of bars 27 is provided transversely crossing the other series of bars. In order that both series may be in substantially the same plane where they are most needed to add to the strength of the construction under tension,

one series may have bent or offset portions 29 (Fig. 3) crossing the other set. The offset bend should be slight and gradual to avoid as much as possible departure from the plane 5 of the series.

Each series of diagonally crossing bars may be provided with hook-like ends 31 which serve advantageously to anchor the bars in the slab.

10 To further strengthen the central region of the slab there may be provided a series of substantially circular bars 33 preferably located directly above the series of crossing bars 25 and 27. These circular bars have 15 diameters progressively increasing outwardly from the center of the slab, and serve to bind the central region of the slab with hoop-like action.

20 To further strengthen the slab sets of straight bars 35 may be provided in the marginal portions of the slab surrounding the central reinforcing unit therefor.

25 Reinforcing units near the upper surface of the slab above the points of the column supports may be constructed as shown at the right of Fig. 1 or as shown at the left of Fig. 1. At the right of said figure some of the radial bars of the unit are hooked about one circular bar, whereas others of 30 said radial bars are hooked about another circular bar. At the left of Fig. 1 all of the radial bars are hooked about the same circular bar.

35 It is the usual practice to fill in the concrete in the mold for the column and permit the same to set for a time before filling in the concrete for the head of the column and for the slab. Before pouring in the concrete for the head of the column, any scum 40 or other foreign material which may have accumulated on the top of the column is cleaned off. Preferably the inner circular bar of the reinforcing unit above the column is made sufficiently large to provide ample 45 room for access to the top of the column to remove such scum or material.

50 The reinforcing means described furnishes a very advantageous construction. The crossing series of diverging bars are arranged to concentrate the greatest reinforcement at the center of the slab where most needed and fan out toward the columns where the reinforcement is less needed, and substantially strengthen the regions which 55 are not covered by the central series of circular bars. The flaring arrangement provides a maximum strengthening of the slab with a minimum material. Fewer bars are necessary than would be required if the diagonal bars extended straight across the center of the slab. If straight bars were used,

obviously substantial portions thereof intermediate their ends would be far from the center where they are most needed.

Since each diagonal bar of the series of 65 diverging bars extends across the central portion of the slab in opposite directions therefrom, it serves to take the place of two short radial bars and by its continuity eliminates the necessity of anchoring the same to 70 the circular bars at the center of the slab.

The small number of bars necessary in the 75 central reinforcement prevents mistakes in the disposition or number of bars used, since the total number is so small that the detection of more or less bars than needed would be almost inevitable. Obviously, if a large 80 number of bars is employed, the detection of such mistakes would be difficult and would require close attention.

85 The central reinforcing unit comprising the series of diagonal crossing bars and circular bars is independent of the reinforcing units above the columns and may be assembled to a templet at the shop or in the yard if desired, and then may be placed as a unit on the mold form.

Having described one illustrative embodiment of the invention without limiting the same thereto, what I claim as new and desire to secure by Letters Patent, is:—

90 The combination with a concrete slab, of supporting columns therefor; reinforcing members in the upper surface portion of the slab diverging from the axes of the columns, circumferential reinforcing members extending transversely to said diverging members; groups of reinforcing members in the lower surface portion of the slab, crossing one another at the center of the 95 slab, and extending diagonally across the slab with end portions intermingling with some of said diverging members, each of said groups having portions in compact relation at the center of the slab to provide ample 100 reinforcement therefor and portions bent laterally outward from the center to provide less reinforcement for areas between the columns and the central area of the slab; central circumferential reinforcing members 105 extending transversely to said groups of diagonal members; and groups of members for reinforcing areas of the slab between the columns surrounding said central circumferential members.

110 In testimony whereof, I have signed my name to this specification, in the presence of two subscribing witnesses.

EDWARD SMULSKI.
